Primary Examiner — Jeffrey D Asch*(74) Attorney, Agent, or Firm* — Banner & Witcoff, Ltd.(57) **CLAIM**

The ornamental design for a handset, as shown and described.

DESCRIPTIONFIG. 1 is a perspective view of a handset showing our new design;
FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The evenly spaced broken lines show portions of the handset that form no part of the claimed design. The dot-dash broken lines, and the evenly spaced broken lines that occur within the outer boundaries of the claim, indicate the boundaries of the claimed design. The broken lines form no part of the claimed design.

1 Claim, 3 Drawing Sheets(56)
